BAKER'S REEL OVEN

Walter R. Reach, Audubon, N.J., assignor, by mesne assignments, to Golden Glow Vending Company, Inc., Philadelphia, Pa., a corporation of Pennsylvania

Filed Nov. 21, 1960, Ser. No. 62,905

Term of patent 14 years

(Cl. D81—10)

Fig. 1.

Fig. 2.

*Fig. 3.Fig. 4.*FIG. 1 is a front perspective view taken from the top and right side of a baker's reel oven embodying my new design, the rear being essentially plain;

FIG. 2 is a front elevational view thereof;

FIG. 3 is a left side elevational view thereof; and
FIG. 4 is a top plan view thereof.

I claim:

The ornamental design for a baker's reel oven, as shown and described.
